DESIGN FOR A COMIC FIGURE

Paul L. Goodale, University City, Mo.

Application October 30, 1939, Serial No. 87,928

Term of patent 14 years

To all whom it may concern:

Be it known that I, Paul L. Goodale, a citizen of the United States, residing at University City, St. Louis County, State of Missouri, have invented a new, original, and ornamental Design for a Comic Figure, of which the following is a specification, reference being made to the accompanying drawing, forming a part thereof, in which Figure 1 is a perspective view, Figure 2 is a front elevational view, and Figure 3 is a side elevational view of a comic figure embodying my new design.

I claim—

The ornamental design for a comic figure, substantially as shown.

PAUL L. GOODALE.
